Filed Sept. 19, 1960, Ser. No. 62,177

Term of patent 14 years

(Cl. D58—26)

FIG. 5.

FIG. 2.

FIG. 6.

FIG. 3.

FIG. 4.

FIG. 1 is a top plan view of a closure for windshield washer reservoir or the like embodying my new design;
FIG. 2 is a side elevational view taken from the top of FIG. 1;

FIG. 3 is a side elevational view taken from the left of FIG. 1;

FIG. 4 is a bottom plan view thereof;

FIG. 5 is a cross-sectional view taken on lines 5—5 of FIG. 1; and

FIG. 6 is a cross sectional view taken on lines 6—6 of FIG. 1.

The sides not shown are substantially like the sides shown.

The dominant features of my design reside in the portions shown in full lines.

I claim:

The ornamental design for a closure for windshield washer reservoir or the like, substantially as shown and described.
